UNITED STATES PATENT OFFICE.

JOHN A. LAMONT, OF CHICAGO, ILLINOIS, ASSIGNOR TO AMERICAN STEEL FOUNDRIES,
OF NEW YORK, N. Y., A CORPORATION OF NEW JERSEY.

TRUSSED SIDE FRAME.

1,165,682.

Specification of Letters Patent. Patented Dec. 28, 1915.

Application filed August 28, 1915. Serial No. 47,760.

To all whom it may concern:

Be it known that I, JOHN A. LAMONT, a citizen of the United States, residing at Chicago, in the county of Cook and State of Illinois, have invented certain new and useful Improvements in Trussed Side Frames, of which the following is a specification.

My invention relates to car trucks and has particular reference to a novel side frame 10 for use in connection therewith.

A desirable result in the construction of car trucks is to provide a side frame which shall combine the requisites of vertical and lateral resistance with light weight and economy in cost of production. I am aware that many forms of built-up side frames have been suggested, but the present form is believed to be of value in that it permits the use of commercial shapes in their best 15 form for securing maximum strength. In the frame shown I have provided for a compression member of rolled shape and of angular form; a channel is preferably used. This shape provides for maximum resistance to bending stresses such as occur in 20 compression. For the tension member I utilize a pair of round rods bent to the required shape. These rods give the best results under tensile stresses and are, of course, 25 very cheaply produced.

The invention will be more readily understood by reference to the accompanying drawings, wherein—

Figure 1 is a side elevation of a side frame 30 constructed in accordance with my invention; Fig. 2 is a bottom plan view thereof; Fig. 3 is a section on the line 3—3 of Fig. 1; and Fig. 4 is a section on the line 4—4 of Fig. 1.

Referring more particularly to the drawings it will be seen that the side frame includes a compression member 10 of rolled channel shape, and a tension member composed of a pair of round rods 11, the ends 40 of which are threaded and accommodate nuts 12. The columns 13 are in the form of a casting to the upper member of which the compression member is secured by means of the rivets 14 and in the lower curved portion 45 of which are provided grooves forming a saddle which accommodates the tension rods 50

11. As a means for securely holding the rods I provide a clamping member 15 which grasps the rods and which member is riveted to the column casting. 55

At the ends of the frame I provide a casting which carries pedestal jaws 16 and is provided with a seat 17, and a recess 18 for the accommodation of the end of the channel compression member 10. The channel is riveted to the casting as best shown in Fig. 1. Diagonal apertures are provided in the casting for the accommodation of the ends of the round rod tension members 11. It will be understood that while I have 60 shown the end castings as including pedestal jaws the construction may be varied by eliminating the jaws and providing a flat surface for resting on a journal box, or I may cast the journal box integral with the 65 casting.

In constructing the side frame, the column casting and the tension members are first united, then the end castings are threaded on to the tension rods and the compression 75 member fitted into the end castings, whereupon the compression member is riveted securely to the column and end castings.

The shape and disposition of parts may be modified somewhat without departing 80 from the spirit of my invention, and I do not, therefore, wish to be limited to the exact form shown and described.

I claim:

1. In a side frame, the combination of an 85 angular compression member, end castings, a column member, the lower edge of which is curved and shaped to provide a saddle, a plurality of tension rods seated in said end castings and occupying the saddle in 90 said column member, and a separate clamping member embracing said rod and riveted to said column member, substantially as described.

2. In a side frame, the combination of an 95 angular compression member, end castings, a plurality of tension rods, a pair of struts separating said compression and tension members and providing a space between the struts for the accommodation of a bolster, 100 the lower ends of the two struts being united, the lower face of the uniting mem-

ber being curved and recessed to provide seats for said tension rods, substantially as described.

3. In a side frame, the combination of 5 an angular compression member, end castings, a pair of intermediate struts spaced apart to provide a bolster opening, the lower portion of which opening is larger than the upper portion thereof, and a plurality of 10 tension rods seated at their ends in the said

end casting and occupying suitable recesses in the lower portion of said strut members, substantially as described.

In testimony whereof I have hereunto signed my name in the presence of two sub- 15 scribing witnesses.

JOHN A. LAMONT.
